UNITED STATES PATENT OFFICE.

PUTNAM MORRISON, OF CHATTANOOGA, TENNESSEE.

KNOCKDOWN ARTICLE OF FURNITURE.

No. 918,352.

Specification of Letters Patent.

Patented April 13, 1909.

Application filed October 23, 1908. Serial No. 459,231.

To all whom it may concern:

Be it known that I, PUTNAM MORRISON, a citizen of the United States, residing at Chattanooga, in the county of Hamilton and State of Tennessee, have invented new and useful Improvements in Knockdown Articles of Furniture, of which the following is a specification.

This invention relates to knockdown articles of furniture and the like, such as kitchen safes, wardrobes, bookcases and other similar structures, and the primary object of the same is to so assemble the several parts or members of the device as to obstruct warping after placement thereof, or if warped when put in place will be straightened by the particular mode of association which will be hereinafter explained.

A further object of the invention is to produce a knockdown article of a strong and durable character and wherein the parts may be more readily assembled than devices of a like nature as heretofore constructed, the parts being replaceable if injured, destroyed or lost at a small cost, the several components of the device being specially constructed for shipment in knockdown condition and convenience in assemblage for display or sale purposes and usage.

The present invention consists in improvements of the structure disclosed by my Letters Patents No. 894,033, July 21, 1908, and No. 906,909, December 15, 1908.

In the drawings: Figure 1 is a front elevation of a safe broken away in parts and shown in section and illustrating the features of the improvement. Fig. 2 is a detail perspective view of the cap or top closure looking toward the under side thereof. Fig. 3 is a perspective view of a portion of the body of the device over which the cap or top closure is fitted. Fig. 4 is a transverse vertical section through the upper portion of the device.

The numeral 1 designates a front frame having suitable openings for a drawer 2 and doors 3, these openings and the drawer and doors being arranged to suit the taste and convenience of the maker. The particular arrangement of this front frame is not essential and may be varied at will. The front frame includes corner posts 4 which extend the full height of the safe and are projected below the bottom of the latter to provide front legs as disclosed in my patents hereinbefore noted. Coöoperating with the front frame 1 is a back frame 5 of the same dimensions as the front

frame and filled with panels 6 and munitions 7 as may be desired and also including corner posts 8 similar to the posts 4 and projected at their lower extremities below the bottom of the device or safe to form rear legs as at 9. All the parts of the front and back frames are preferably united to the posts 4 and 8, and said frames present complete organization of their components when ready for service or assemblage with the remaining parts of the device or safe. The front posts 4 of the frame 1 and the posts 8 of the frame 5 have grooves 10 formed in their inner faces, as clearly shown by Fig. 3, the said grooves being directly opposite each other and parallel, and run lengthwise of the posts. These posts 4 and 8 are also transversely bored as at 11, see Figs. 1 and 4, the several bores being in alinement in the pairs of posts to removably receive rods 12 arranged at intervals and serving to draw the front and back frames together in assembled relation to the remaining parts of the device or safe and also acting as effective auxiliaries in securing the parts of the safe in practical associated relation.

At regular intervals throughout the vertical extent of the device or safe, or at different distances apart, as may be desired, shelves 13 are disposed and rendered accessible through the medium of the doors 3, and between the shelves are a plurality of end panels 14 corresponding in number to the shelves, the said panels varying in vertical extent in accordance with the distance between the shelves 13 and between the uppermost shelf and the top of the safe, which uppermost shelf or top consists in the present instance of a cap or top closure 15 of any preferred construction but as shown preferably overhanging the upper ends of the adjacent end panels. The panels 14 slidably engage the grooves 10 in the inner faces of the posts 4 and 8 and practice has demonstrated that the length of these end panels should be equal to the width of the shelves plus the depth of the said grooves 10 to give the best results.

In the present construction of safe which is shown as an illustration of one embodiment of the invention, the shelves 13 have their ends flush with the outer surfaces of the panels 14 so that in the event that any one of the shelves starts to spring upward or become misshapen in an upward or a downward direction a resistance will be set up by the ends of the panels engaging therewith or bearing against the upper and lower

sides of the opposite extremities of each shelf. In other words, the shelves and end panels contribute to prevent warping of the one with respect to the other, and in performing this function the whole series of shelves and end panels, and in the present construction the cap or top closure also, are united or conjointly act and thus increase the resisting force to irregular position of the parts due to shrinkage or warpage.

When the correct number of shelves and panels has been placed in position or assembled in coöperative relation and the rods 12 inserted through the posts 4 and 8, the operation of tightening and finally clamping the end panels and shelves in place is pursued. Prior to tightening up the rods 12 the shelves and panels are successively disposed in place and in contradistinction to the retention of the said panels and shelves in place solely by the rods 12 as in my previous structures, the cap or top closure 15 in the present improvement constitutes the essential means for holding the panels downwardly in close contact with the shelves, or for exerting on the panels a downward pressure, primarily exerted through the uppermost panels, to maintain the panels and shelves in tight assemblage or so that the ends of the panels will firmly engage the ends of the shelves to hold the latter in true position and also prevent the panels from moving or slipping out of place after the several parts of the device or safe are disposed in operative relation. The cap or top closure 15 has a depending surrounding flange or frame 16 which snugly fits over and embraces the front and back frames and ends of the device or safe, as shown, and is mortised or recessed as at 17 to receive the upper projecting portions of the posts 4 and 8. Front and rear screw threaded fastenings or bolts 18 depend from the top of the cap or closure 15 and engage angle brackets 19 secured to the inner opposing sides of the posts 4 and 8 within the upper portion of the device or safe, nuts 20 being used in this instance to hold the fastenings or bolts 18 in engagement with the brackets, as clearly shown by Fig. 4. Though this specific form of fastening means is advantageous, it will be understood that any analogous fastening may be employed that has a function to draw the cap or top closure 15 tightly over the upper portion of the device or safe and which fastening may be readily detached or the parts thereof separated so as to carry out the knockdown feature of the complete device. The upper ends of the uppermost panels project slightly above the upper terminals of the posts 4 and 8, as at 21, and contact directly with the lower surface of the cap or top closure 15, see Fig. 4, and by this means all of the panels have a downward pressure exerted thereon when the cap or top closure 15 is applied and

secured by the drawing fastenings 18 engaging the brackets 19. It will be observed that, owing to the positive resistance set up by the cap or top closure when applied and in contact with the upper ends of the uppermost panels, it will be impossible for the panels to move vertically or become displaced and hence the engagement of the ends of the panels with the ends of the shelves will be positive and reliable and at all times uniformly maintained, the tie rods 12 acting as effective auxiliaries in drawing the front and back frames closely together and holding the front and rear vertical edges of the panels in engagement with the grooves 10 in the front and back posts 4 and 8.

A further feature of the improvement consists in applying stop or guard strips 22 over the engaging ends of the panels and shelves. These guard strips are secured to each panel above the lower end of the latter and overhang the adjacent shelf end and a portion of the upper end of the panel next below and completely cover the joint between the panel and shelf ends and prevent sliding movement or horizontal displacement of the shelves. These stops or guards will always remain connected to the panels carrying the same so as to be ready for application without requiring attachment thereof when it is desired to set up the device or safe. The outer surfaces of the stops or guards 22 are flush with the outer surfaces of the end posts 4 and 8 and said stops or guards are also of such length as to fit within the outer portions of said posts, as clearly shown by Figs. 1 and 3.

As shown by Fig. 1, the lowermost shelf 13 is illustrated as bearing upon the lower pair of tie rods 12 but this construction is not to be understood as the only means that could be employed for serving as the bottom resistance to the lowermost shelf and the series of panels and shelves thereabove. The construction disclosed by my Patent 906,909, hereinbefore referred to, and wherein the lowermost shelf bears at opposite extremities on shoulders carried on the legs extending from the posts, might be used, or any other analogous supporting means might be adopted, it being only essential that sufficient resistance be set up in relation to the lowermost shelf to render it positive as a supporting means for the panels and shelves above under pressure exerted by the cap or top closure on the plurality of panels and directly engaging the uppermost pair of panels.

A knockdown safe has been illustrated as embodying the features of the invention, but it is obvious that the same structure might be adopted in other analogous containing devices having knockdown characteristics.

What is claimed as new is:

1. A knockdown article of furniture comprising front and back frames, a plurality of

shelves, panels interposed between the shelves and engaging the frames, the uppermost panels projecting above the upper edges of the frames transversely extending connecting devices engaging the opposite extremities of the front and back frames and serving to draw the latter toward each other to hold the panels and shelves in place, and a cap or top closure fitted over the upper extremity of the article and bearing on the upper ends of the uppermost panels to exert a downward pressure on all the panels and shelves, the cap or top closure being provided with fastening means to hold the same in secured position.

2. A knockdown article of furniture comprising front and back frames, shelves, end panels, the uppermost panels projecting above the upper edges of the frames, transversely extending tie devices, the edges of the panels and opposite extremities of the shelves being held in engaging relation, a top closure contacting with the upper ends of the uppermost panels and exerting a downward pressure on all the panels and shelves, and fastening means for drawing the top closure downwardly against the said uppermost panels and frames, the lowermost shelf acting as a resisting supporting means for the panels and shelves thereabove.

3. A knockdown article of furniture comprising front and back frames, shelves, end panels, the uppermost panels projecting

above the upper edges of the front and back frames, transversely extending tie devices, 35 the edges of the panels and opposite extremities of the shelves being held in engaging relation, and a top closure fitted over the upper end of the article and engaging the upper ends of the uppermost panels and provided 40 with drawing fastening devices projecting from the lower side of the closure and operative within the article to set up a downward pressure on the panels and shelves.

4. A knockdown article of furniture comprising front and back frame members, shelves, end panels having guard strips attached to the outer sides of their lower extremities, the upper and lower edges of adjacent panels bearing against opposite sides of 50 the extremities of the shelves and the guard strips loosely overhanging and covering the joints between the ends of the panels and the shelves between the front and back frame members and independent of the latter, and 55 means for holding the frames, shelves, and panels in assembled relation, the guard strips being simultaneously applicable and movable with the panels.

In witness whereof I have hereunto set my 60 hand in presence of two subscribing witnesses.
